UNITED STATES PATENT OFFICE

156,292

DESIGN FOR A HOBBYHORSE

Elmer Szantay, Chicago, Ill., assignor to Sandee
Manufacturing Company

Application March 6, 1948, Serial No. 144,951

Term of patent 3½ years

(Cl. D34—15)

To all whom it may concern:

Be it known that I, Elmer Szantay, a citizen of the United States, residing at Chicago, county of Cook, and State of Illinois, have invented a new, original, and ornamental Design for a Hobbyhorse, of which the following is a specification, reference being had to the accompanying drawing, forming a part thereof, in which—

Fig. 1 is a top plan view of the hobbyhorse, showing my new design;

Fig. 2 is a side elevational view thereof, and
Fig. 3 is a front elevational view thereof.

I claim:

The ornamental design for a hobbyhorse, as shown.

ELMER SZANTAY.
